HAIRPIN OPENER

Gerald K. Hopkins, Essex County, Mass.

Application December 3, 1947, Serial No. 789,464

2 Claims. (Cl. 132—1)

1

This invention relates to improvements in hairpin openers particularly of the type known as "bobby pins." The particular object of the invention is to provide a device which will separate the side members of the "bobby" pin preparatory to its use in the hair.

It has been allegedly found that the common method of inserting "bobby" pins between the teeth develops ridges in ladies' teeth from this constant usage. However this may be, the device of the invention is a simplified means of spreading the side members of the "bobby" pins and to provide a construction whereby the "bobby" pin opener may be made in the form of a ring supported on the finger in a manner to facilitate positioning of the hairpin thereon and removing the same thus saving time and eliminating the difficulties involved in the present methods of spreading "bobby" pins.

A more specific object of the invention is to provide such a finger ring opener with a guide for the long prong of the pin in order that the said prong may be slid into a suitable trough for guiding until the said long prong passes through a hole in the guide provided for the purpose.

A further object of my invention is to enable the "bobby" pin opener to be so arranged that the guide portion of the opener occupies such a position relative to the finger upon which the ring is held that the "bobby" pin may be pointed towards the guide in a direction parallel with the length of said finger.

The invention will be more specifically explained and better understood by referring to the accompanying drawing in which Fig. 1 represents my improved "bobby" pin opener in isometric view. Fig. 2 is a view of the "bobby" pin opener in the form of a ring with the guide integral therewith and illustrating the angular relationship of guide and ring; Fig. 3 is a similar view to Fig. 2 with the long prong of the "bobby" pin extending farther through the opening in the guide and the short prong slid up the trough of the guide, and Fig. 4 is a bottom view of the ring and guide illustrating that the ring is split for adjustment to fit the finger.

Referring more specifically to the drawing, like numerals refer to like parts throughout the various figures of the drawing.

In Fig. 1, 1 represents the ring portion of the device and preferably flattened at the top 2; 3 represents a guide or locator extension provided with an opening 4, and 5 represents a split portion of the ring 1 at the bottom whereby the ring is self adjusting to fit varying sizes of fingers.

2

The locator or guide 3 is trough-shaped as illustrated in Fig. 1 the bottom level of the trough being illustrated by the shaded line at 6, Fig. 1. Fig. 2 illustrates the relation of the "bobby" pin to guide or locator 3 when the "bobby" pin 7, Figs. 2 and 3, is being inserted through the opening 4 in the guide 3. It will be seen from Figs. 2 and 3 that the direction of insertion of the "bobby" pin in the guide is not laterally with reference to the finger but parallel thereto; that is when the "bobby" pin is inserted in the trough 6 of the guide the long prong of the "bobby" pin is slid upwardly in the trough 6, Fig. 1 until it finds the opening 4. This is a considerable advantage as it does not involve trying to find the "bobby" pin opening at right angles or at any other angle to the plane of the ring on the finger. With this arrangement the "bobby" pin may be opened either before the fingers are raised to the back of the head; or after one hand of the operator is employed in holding the hair the other hand may be used to slide the "bobby" pin along the guide 3 and open the "bobby" pin at that position. In this manner it does not require two hands to open the "bobby" pin, but one hand of the operator may be employed in holding the hair while the other opens the "bobby" pin by means of the ring and guide on the finger of the hand which is holding the hair. The trough-shaped guide is very effective in this connection and once the long prong of the "bobby" pin strikes the trough 6 on the guide 3 it requires no effort to slide it along and to automatically find the opening 4 through which the long prong of the "bobby" pin is immediately projected, and thumb 8, Fig. 2 may be employed to push the "bobby" pin through and the short prong slid up the trough 6 as the long prong extends farther through the opening 4. The "bobby" pin is now effectively spread and may be withdrawn by the operator with the finger of the operating hand inserted between the prongs of the "bobby" pin to keep the latter open until it is inserted in the hair.

It will be seen that with the specific construction of locator or guide and its relationship to the direction of operation with reference to the ring, the spreading of the "bobby" pin is almost automatic and there is no fumbling around to find the proper direction or location of opening of the pin. Also the operator may have one hand employed in holding the hair while the other hand may be employed to open the pin.

What I claim as new and desire to secure by Letters Patent of the United States is:

1. A "bobby" pin opener comprising in com-

bination a spreader formed like a trough and having an opening in the bottom of the trough-like spreader to receive the longer prong of a "bobby" pin, and said spreader attached to the top surface of a finger-ring beginning on a plane coincident with the top surface of the ring and extending angularly upwardly therefrom.

2. A "bobby" pin opener comprising a finger-ring having a partially flattened top surface, in combination with a V-shaped trough having an opening in the bottom thereof, and said trough extending rearwardly and angularly upwardly

from the partially flattened top surface of the ring.

GERALD K. HOPKINS.
